SPARK-PLUG.

1,274,002.

Specification of Letters Patent. Patented July 30, 1918.

Application filed June 20, 1917. Serial No. 175,918.

To all whom it may concern:

Be it known that I, RAYMOND CHAMPLIN, a citizen of the United States, residing at Bremerton, in the county of Kitsap and State of Washington, have invented new and useful Improvements in Spark-Plugs, of which the following is a specification.

This invention relates to improvements in ignition devices for internal combustion engines, referring particularly to an improved spark plug.

In carrying out the invention I propose primarily to provide a spark plug having an electrode which is adapted for automatic movement to maintain the surface in a clean condition by friction against portions of the plug, and to prevent pitting or corrosion of any particular portion of the surface.

I further propose to mount the movable electrode in such a manner that the distance between the electrodes will remain substantially the same.

Another object is to arrange the movable electrode in such position that the gas in the cylinder will have free access to the spark.

One form of the invention is described in the specification below, set forth in the claims, and delineated in the drawings, in which—

30 Figure 1 is a side elevation of a plug constructed in accordance with the present invention.

Fig. 2 is a transverse section taken on the line 2—2 of Fig. 1.

35 Fig. 3 is an end view.

In the drawings, the numeral 1 designates a spark plug having the usual shell 2 provided with a hollow screw threaded cylindrical portion 3 for securing the plug in the 40 spark plug opening of a cylinder. Mounted in the shell 2 in the customary manner is the insulating element 4 surrounding the center electrode 5 having the end projecting inwardly for discharge of the spark to an 45 electrode on the shell 2.

In the present embodiment of the invention the center or insulated electrode 5 is of the usual type, but it is to be understood that I may when desired embody in its construction the principle here shown as utilized only in the non-insulated electrode.

In accordance with the invention the lat-

ter electrode comprises a ball 7 of conducting material and preferably of metal such as commonly used for spark plug electrodes, 55 and is seated against the edge of an opening 8 in the shell 2 of such diameter as to partly receive the ball 7 but not large enough to permit entrance. To facilitate the construction of the plug and permit free access of 60 gas to the spark, the portion of the shell 2 formed with the opening 8 preferably constitutes a projection 8' of one side of the shell 2 as clearly shown in the drawings. For retaining the ball in position means are 65 provided here shown as angularly disposed pins 9 secured in bores in the shell adjacent the opening 8 and extending sufficiently close to the ball 7 to prevent bodily movement of any appreciable degree, but adapted 70 to permit rotation of the ball 7 under the influence of vibration such as that resulting from the operation of the engine. By this rotation in contact with the preferably sharp edge of the opening 8, the ball 7 is maintained in the clean condition most favorable 75 for passage of the spark; and the continually changing point of reception of the spark prevents pitting or corrosion and the consequent widening of the spark gap between the ball and the center electrode 5.

The latter extends to a proper sparking distance from the ball, and the terminal portion 10 is preferably bent toward the ball to permit the spark to discharge from the 85 end. It will be evident that when desired a second ball 7 may be mounted in the shell 2 in a manner similar to the single ball shown, and that the two balls may be arranged in proximity and at equal distance from the 90 center electrode 5 so that the corrosive action of the spark will be divided between the two balls.

It is to be understood that I do not limit myself to the particular construction described and shown, nor even to the application of the invention to spark plugs, as I am aware that it may be utilized to advantage in many other devices.

What I claim is:—

1. A spark plug comprising a shell part having a projection at one side thereof provided with a transverse opening therein, a spherical member in said opening, and

means for holding the member in said opening while allowing the same to have rotary movement therein.

2. A spark plug comprising a shell having one side provided with an extension at its lower end having an opening therein, a spherical member in said opening, pins lo-

cated in said extension on each side of the opening and loosely engaging the member to hold the same in place, and a central electrode having its lower end bent toward the spherical member.

In testimony whereof I affix my signature.

RAYMOND CHAMPLIN.
